UNITED STATES PATENT OFFICE.

JOHN J. GILLESPIE, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

GRINDING-MACHINE.

1,268,341.

Specification of Letters Patent.

Patented June 4, 1918.

Application filed November 6, 1914. Serial No. 870,690.

To all whom it may concern:

Be it known that I, JOHN J. GILLESPIE, a citizen of the United States, residing at Boston, in the county of Suffolk and State 5 of Massachusetts, have invented certain Improvements in Grinding-Machines, of which the following description, in connection with the accompanying drawings, is a specification, like reference characters on the 10 drawings indicating like parts in the several figures.

This invention relates to grinding machines and particularly to machines for grinding or sharpening cutting dies such 15 as are used for dieing out blanks from sheet material. Dies of this character are used extensively in the manufacture of boots and shoes, especially for cutting out soles and uppers. In such operations usually the 20 sheet of stock is supported upon a cutting block, the die is placed in the selected position with its cutting edge resting upon the stock, and a power operated beam is then brought into engagement with the upper or 25 blunt edge of the die to force the die through the stock and cut the blank. It is important in such operations that the cutting edge of the die shall be properly ground, since too long a bevel upon the edge 30 will render the edge too easily subject to breakage and cause the die under some conditions to be forced unduly into the cutting block, while too short a bevel will prevent the die from making a clean cut through the 35 stock. It is important also that all portions of the die be ground to the same extent so that the distance from the cutting edge to the blunt edge shall be constant along all portions of the blade, since any 40 variation in this respect would necessitate that some portions of the cutting edge be forced farther into the cutting block than other portions and would thus cause the die to stick in the block and to mar unduly the 45 surface of the block.

Objects of this invention are to provide a machine which may be used conveniently to grind a predetermined and constant angle of bevel upon all portions of the cutting 50 edge of a die and to grind all portions of this edge to the same extent with reference to the distance between the opposite edges, including also provision for suitable adjustments to accommodate dies of different

heights and to insure the formation of substantially the same angle of bevel upon the blade notwithstanding the wear of the grinding member.

It will be readily understood from the following detailed description that the invention is not limited in its application to the grinding of dies of any particular shape or character or to dies adapted for any particular use, nor, in fact, necessarily to the grinding of blades in the form of dies, since 60 obviously many of the features of the invention may be employed advantageously in the grinding of tools of various shapes and forms and adapted for various uses.

The features of the invention, including 70 certain details of construction and combinations of parts, will now be described with reference to the accompanying drawings and pointed out in the claims.

In the drawings,

Figure 1 is a perspective view of a machine in which the invention is embodied;

Fig. 2 is a side elevation of the machine showing a portion of a blade in position to be ground, and

Figs. 3 and 4 show details of the guiding and positioning means for the blade.

The illustrated preferred form of the invention comprises a frame 2 which is portable and is provided with a handle 4 whereby the machine may be held by the operator in one hand while the die or like article is held in the other hand and presented for grinding. It should be understood, however, that if desired the machine may be secured in any convenient manner to a suitable support and used as a bench grinder, and that such use of the machine is contemplated as within the province of the invention. Pivoted at 6 to the frame 2 is a support 8 provided with a bearing or bearings 10 for a grinding wheel 12. This wheel is comparatively thin and has a transversely curved peripheral surface, since a wheel of this form is found particularly 85 advantageously in grinding dies having curved blades which may be deeply concaved at portions of the surface presented for grinding. The wheel has a projecting shaft end 14 to which may be secured a 90 flexible power transmission shaft.

In the front of the frame 2 is a dovetailed groove in which is mounted a slide 16 pro-

vided with a slot 18 embracing the shank of a screw 20 which is threaded in the frame. Positioned upon the front of the slide 16 is a bracket 22 provided with a slot 24 which also embraces the shank of the screw 20, the screw thus serving to clamp both the bracket and the slide in position upon the frame 2. The bracket 22 serves as a guide upon which to position the blunt edge of 10 the blade and is extended to provide a bearing for a considerable portion of the blade so as to maintain the cutting edge in the same plane as it traverses the wheel. A portion of a die blade is shown at *a* in Fig. 15 2 in position for grinding. The bracket 22, by reason of the slot 24, is adjustable toward and from the wheel so as to accommodate dies of different heights or blades of different widths.

20 The slide 16 has a projecting portion 26 to serve as a guide or positioning member for the lateral surface of the blade. This guide is formed with a narrow edge 28 to engage the blade so as to insure that the 25 lateral position of the blade at the point of grinding shall be invariable irrespective of the longitudinal curvature of the blade, this construction of the guide being particularly useful where a concave surface such as is 30 presented by the reentrant portions of die blades is presented to the grinding member. The edge 28 is located in the plane of the grinding wheel so as to engage the die immediately below its point of contact with 35 the wheel, and the guide or support 22 preferably is so positioned that its die supporting surface is substantially perpendicular to the edge 28 which will thus engage the lateral surface of the blade on a line substantially perpendicular to the edges of the 40 blade and to the line of longitudinal curvature of the blade where such curvature is present. The edge 28 is broken away at 30 so that the guide has substantially a two-point bearing on the blade near the opposite 45 edges thereof. This insures that any surface irregularities on the intermediate portion of the blade shall have no effect in determining the position of the blade during 50 grinding.

The wheel 12, it will be noted, projects over the guides 22 and 26 in position to 55 grind a bevel upon the edge of a blade presented for treatment. The wheel support 8 is formed with a rearward projection 32 provided with a bore or slot to receive the shank of a screw 34 which is threaded in the frame 2 and thus serves as a stop to limit 60 swinging movement of the support in the direction to carry the wheel toward the work. A spring 36 positions the support 8 normally at the limit of movement determined by the stop 34, but permits the support to be swung in the opposite direction through 65 adjustment of the stop or in response to

any unusual pressure. The support 8, it will be understood, is adjusted by means of the screw 34 and the spring 36 to position the grinding wheel in proper relation to the work guides, and by this adjustment, in 70 combination with suitable adjustment of the die support 22, the wheel may be so positioned with reference to the guide 26 as to grind, within limits, the angle of bevel desired. The support 8, moreover, is so pivoted 75 and arranged with reference to the guide 26 that as the wheel wears away it may be maintained by adjustment in such relation to the guide as to grind substantially the same angle of bevel upon blades of equal 80 width.

In the use of the machine, in addition to the adjustment of the wheel 8 above explained, the guide or support 22 will be suitably positioned in accordance with the 85 height of the die or the width of the blade which is to be ground. After the proper 90 adjustments have been made the operator supports the machine in one hand by the handle 4 and holds the die or like article 95 in the other hand, positioning the blunt edge and the side of the blade respectively upon the guides 22 and 26 and moving the die and the machine relatively to cause all portions of the cutting edge to traverse the 100 wheel and to be ground to the extent permitted by the adjustment of the parts. If it is necessary or desirable to grind the blade to a greater extent than is permitted by the first adjustment, the guide 22 may be 105 readjusted or the screw 34 may be loosened to permit the spring 36 to swing the wheel 12 slightly toward the work, and the relative traverse of the blade and the wheel may be again effected in the same manner 110 as before. Under ordinary conditions either of these adjustments will be sufficient to insure the formation of a sharp edge on the blade without altering materially the angle of bevel; but it will be understood that in 115 order to avoid changing the angle of bevel, if any considerable portion of the blade is to be ground away, both the adjustments should be resorted to, so as to compensate for both the wear of the wheel and the 120 decrease in the width of the blade.

Although the invention has been explained with reference to a machine having the precise details of construction shown and described, it should be understood that this 125 is simply by way of illustration in order that the invention may be clearly understood, and that various embodiments are comprehended within the spirit and scope of the claims.

Having described the invention, what I claim as new and desire to secure by Letters Patent of the United States is:—

1. In a machine for grinding cutting dies or the like, the combination with a grinding 130

member, of positioning means for the die to be ground constructed and arranged for engagement with the blunt edge and the lateral surface of the die blade to determine the position of the cutting edge with reference to the grinding member, the machine being constructed to permit relative movement between the die on the one hand and said positioning means and grinding member together on the other to cause the grinding member to engage successively different portions of the cutting edge of the die.

2. In a machine for grinding cutting dies or the like, the combination with a grinding member, of means for supporting the die blade by its blunt edge to present the cutting edge in position to be ground by said member, and a guide for the lateral surface of the blade arranged to engage said surface near both edges of the blade.

3. In a machine for grinding cutting dies or the like, the combination with a grinding member, of guiding means upon which to position the blunt edge of the die and with relation to which the die is movable to present different portions of its cutting edge to the grinding member, said means being constructed and arranged to maintain the cutting edge of the die blade in the same angular relation to the grinding member, and a guide for the lateral surface of the blade having a narrow edge portion so arranged with reference to said first named guiding means as to engage the blade on a line substantially perpendicular to the edges of the blade.

4. In a machine for grinding cutting dies or the like, the combination with a grinding member, of guiding means upon which to position the lateral surface of the die blade and with relation to which the die is movable to bring different portions of its cutting edge into engagement with said member, said means being formed to provide two bearing points for the blade near the opposite edges thereof in a plane substantially parallel to the plane of the grinding member.

5. In a machine for grinding cutting dies or the like, the combination with a grinding member, of a guide constructed to engage an extended portion of the blunt edge of the die blade to position the cutting edge in proper angular relation to the grinding member, and a guide for the lateral surface of the blade having a die engaging edge substantially perpendicular to the die engaging portion of said first named guide.

6. A machine for grinding cutting dies or the like having, in combination, means upon which to position the blunt edge and the lateral surface of the die blade and with relation to which the die is movable during the grinding operation, and a grinding member arranged with reference to said

means to grind a bevel on the cutting edge of the blade, said member and means being relatively adjustable to accommodate dies of different heights while maintaining a relation for grinding the same angle of 70 bevel on the different dies.

7. In a machine for grinding cutting dies or the like, the combination with a grinding member, of a pair of guides arranged to engage respectively the blunt edge and 75 the lateral surface of the die blade to present the cutting edge of the blade in position to be ground by said member, the edge guide being adjustable with reference to the other guide to accommodate dies of different heights.

8. In a machine for grinding cutting dies or the like, a grinding wheel having a transversely curved peripheral surface, and guiding means upon which to position the die to 85 be ground comprising a member having a narrow edge in the plane of the wheel for determining the lateral position of the die blade at its point of engagement with the wheel.

9. In a machine for grinding cutting dies or the like, the combination with a grinding member, of guiding means between which and the die there is provision for relative movement longitudinally of the die blade, 95 said means comprising a member having a narrow edge substantially perpendicular to the line of longitudinal curvature of the blade in position to engage the lateral surface of the blade directly opposite to that portion of the blade which is in engagement with the grinding member.

10. In a machine for grinding cutting dies or the like, the combination with a grinding wheel, of guiding means arranged to 105 be engaged by the blunt edge and the lateral surface of the die blade and with relation to which the die is movable to bring different portions of its cutting edge successively into engagement with the wheel, said wheel 110 and the guiding means being relatively arranged to cause the wheel to grind a bevel on the cutting edge of the die, and a support for the grinding wheel arranged for adjustment to present the wheel, as its diameter decreases through wear, in position to 115 grind substantially the same angle of bevel on the die.

11. In a machine of the class described, the combination with positioning means for 120 the work, of a grinding member, a support for said member mounted for swinging movement to carry the member toward or from the work, means for limiting movement of the support in the direction to carry the 125 member toward the work, and resilient means for opposing movement of the support in the opposite direction.

12. In a machine of the class described, the combination with positioning means for 130

- the work, of a grinding member, a support for said member mounted for swinging movement to carry the member toward or from the work, an adjustable stop for variably limiting movement of the support in the direction to carry the member toward the work, and a spring arranged to position the support normally at the limit of movement determined by the stop.
- 10 13. A machine of the class described having, in combination, a portable frame, a handle whereby the frame may be supported, a grinding wheel carried by the frame, a connection for applying power to the wheel, and means on the frame arranged with reference to the grinding wheel to position a die blade or the like with its cutting edge in engagement with the periphery of the wheel.
- 15 14. In a grinding apparatus, the combination with a grinding member, of a guide member having a narrow edge to engage the lateral surface of a blade to be ground, the

guide edge extending transversely of the blade and said guide and blade being movable relatively to one another in the grinding operation, the narrowness of the guide tending to insure an invariable lateral position of the blade at the point of grinding irrespective of its curvature. 25

15. In a grinding apparatus, the combination with a grinding member, of a plurality of guide members, the guide members and object to be ground being movable relatively to one another in the grinding 30 operation, and means constructed and arranged to permit the guide members to be independently adjusted.

In testimony whereof I have signed my name to this specification in the presence 40 of two subscribing witnesses.

JOHN J. GILLESPIE.
